UNITED STATES PATENT OFFICE.

HENRY J. SOMMERKAMP, OF GLEN RIDGE, NEW JERSEY, ASSIGNOR TO CONSOLIDATED SAFETY PIN COMPANY, OF BLOOMFIELD, NEW JERSEY, A CORPORATION OF NEW JERSEY.

BRUSH ATTACHMENT FOR ERASERS.

1,176,783.

Specification of Letters Patent. Patented Mar. 28, 1916.

Application filed March 10, 1915. Serial No. 13,548.

To all whom it may concern:

Be it known that I, HENRY J. SOMMERKAMP, a citizen of the United States, residing in Glen Ridge, county of Essex, and 5 State of New Jersey, have invented new and useful Improvements in Brush Attachments for Erasers, of which the following is a specification.

This invention relates to brush attachments for disk erasers, and has for its object the provision of a readily removable attachment which is adapted to rigidly hold the brush block, the parts being preferably secured together without the employment 15 of rivets, screws or other non-integral means for rigidly maintaining the parts in their assembled condition.

My invention is fully set forth in the accompanying specification and drawing 20 forming a part thereof in which—

Figure 1 is an elevation of my attachment applied to a disk eraser; Fig. 2 is a vertical central section thereof; Fig. 3 is a plan view of a metal blank from which the frame of 25 said attachment is constructed.

Referring to the drawings and the construction shown therein, the reference numerals 1, 1' designate the respective lateral spring arms of a brush holder, the same 30 being provided with offset bosses 2, 2', respectively, which are adapted to snap into engagement with the central aperture, such as a of the disk eraser, as indicated by the reference letter b.

35 The arm 1' is provided with a lug or ear 3 which is adapted to envelop the opposite arm 1 when the blank shown in Fig. 3 has been shaped by folding as shown in Figs. 1 and 2, thereby it is possible without any 40 rivets to securely lock the loop 4 formed by said folding or bending of the blank, and the brush block 5 which is adapted to snugly fit within said loop 4. Said brush block is provided with the usual horse hair or other 45 bristles c which project downwardly below said loop 4 and preferably a portion of said brush block engaged by said loop 4 is reduced so as to form collars 6, 6' and there- 50 by more definitely prevent any lateral or vertical movement of said brush within said loop. Obviously however these collars may be omitted, and if desired one or more ribs (not shown) may be formed on the inner face of said loop 4, and said brush

block may be provided with corresponding 55 peripheral grooves adapted to receive said ribs (also not shown).

The holder is preferably constructed of spring brass and may be nickel-plated if desired, and furthermore, the said loop of 60 the holder may be co-extensive with the brush block in order to give a more finished appearance to the article.

Various other modifications may be made without departing from the spirit of my 65 invention as herein claimed.

Another important feature of the invention resides in the fact that the brush holder is offset with respect to the longitudinal axis of the arms, whereby a more 70 convenient grip is provided which permits of the more convenient operation of said brush, and furthermore with the brush so arranged its longitudinal axis is practically parallel to the vertical diameter of the brush 75 and to one side of said diameter when the said brush is held in vertical position, whereby observation of the surface to be stroked by said brush is made easier than were the axis of the brush in direct alignment with the vertical diameter of the 80 eraser when the same is held in a vertical position as is the case in prior structures.

Having thus described my invention, what I claim and desire to secure by Letters 85 Patent is:—

1. A brush holder for disk erasers consisting of a single strip of metal folded to form two substantially symmetrical arms extending parallel to one another and spaced 90 apart sufficiently to permit of the same spanning a disk eraser, an off-set brush-socket formed by said folded portion of said strip and an ear projecting beyond the edge of one of said arms adapted to be 95 folded around and grip the other of said arms, and a brush block provided with a brush inserted within the folded portion of said metal strip and removably secured therein by said ear whereby said brush is 100 held in a position parallel to said arms and off-set therefrom.

2. A brush holder for disk erasers consisting of a single strip of metal folded to form two substantially symmetrical arms extending parallel to one another and spaced apart sufficiently to permit of the same spanning a disk eraser, an off-set brush-socket 105

formed by said folded portion of said strip, and a brush block, provided with a brush, inserted within said folded portion and rigidly secured therein, whereby said brush is held in a position parallel to said arms and offset therefrom.

Signed at Bloomfield, county of Essex

and State of New Jersey, this 8th day of March, 1915.

HENRY J. SOMMERKAMP.
